ATTORNEY

UNITED STATES PATENT OFFICE

RICHARD STAUDT, OF SAGINAW, MICHIGAN

HOSPITAL BED

Application filed January 11, 1930. Serial No. 420,032.

This invention relates to hospital beds equipped with mechanism for easily and conveniently handling a patient in prone position without bodily jarring or twisting and without exerting on the patient any uncomfortable degree of manual force or handling.

The objects of the invention are to provide a relatively inexpensive mechanism that is adapted to raise the patient clear of the mattress and to support him above it, to remove the mattress from the bedstead while the patient is so supported and then to lower the patient any desired amount, even nearly or quite to the floor, meanwhile supporting his body hammock-wise, avoiding all tendency to roll. The patient may thus be lowered into a bath tub on the floor and the rate and amount of immersion can be regulated by the lowering mechanism.

Another object of the invention is to provide means for lifting the patient out of the bath slowly or quickly as desired and without jar or vibration and to provide means for easily and quickly changing the supporting sheet on which the patient lies, after the bath is finished. This is all done without disturbing the patient or materially altering his posture.

A still further object is to provide in the lifting and supporting mechanism means to facilitate turning or rolling the patient from side to side in order to change his position, without using any considerable amount of manual force upon his body.

With the foregoing and certain other objects in view, which will appear later in the specification, the invention comprises the devices described and claimed and the equivalents thereof.

In the drawing Fig. 1 is a top plan view of a bedstead embodying my invention, the supporting sheet being shown as it appears while in the act of being removed and replaced by a fresh sheet.

Fig. 2 is an end view, partly broken away, of the parts shown in Fig. 1.

Fig. 3 is a fragmentary transverse sectional view, partly diagrammatic, showing the supporting sheet in raised position, the removal

of the mattress being indicated by dotted lines.

Fig. 4 is a fragmentary transverse sectional view taken on the line 4—4 of Fig. 1.

As is clearly shown in the drawing, the structure which I have chosen for purpose of illustration as typically embodying my invention consists in the bedstead comprising the usual head piece 1 and foot piece 2 connected by the usual side rails 3—3.

To support the mattress transverse rails 4—4 are provided at the head and foot. A mattress frame, which may be of usual form, has its ends 5 slidably supported on the rails 4, so the mattress may be removed from the bedstead by sliding out sidewise, as indicated by the dotted lines at the right in Fig. 3.

In applying my invention to a bedstead of the kind above described two horizontal bars 6, 6 are arranged lengthwise the bed and are normally positioned at the sides of the bed at the longitudinal edges of the mattress, as shown in Fig. 2.

A strong flexible fabric sheet 7 is removably secured at its longitudinal margins to the respective bars 6, 6. The means of securing the sheet to the bars is indicated in Figs. 1, 3, 4, where eyelets 7a are provided in the sheet and the edges of the sheet are lashed to the bars 6 by means of lacings 7b. These lacings are convenient for removing the sheet 7 and replacing it with a fresh one, as will be described later.

For the purpose of my invention it is only essential that the bars 6, 6 shall be mounted in such a way that they can be raised simultaneously and that they can be lowered below the level of the mattress-supporting rails 4 and that in being so lowered they shall approach each other as shown in Fig. 4.

Any type of bar actuating mechanism may be employed, but for purpose of illustration and as a preferred embodiment of bar actuating means I have diagrammatically shown cords 8 secured to the ends of the bars 6, extending upwardly at the four corners of the bed where they are rove through suitable guideways 9. The two cords at each end of the bed are extended downwardly and fas-

tended to a winding shaft 10 that may be operated by a crank 11 whereby the two bars 6, 6 may be simultaneously raised and lowered.

16 To cause the bars to move toward each other when they are lowered below the mattress level the bars 6 have their ends provided with arms 12 that are pivoted as at 13 to a stationary support on the bedstead. The 20 operation is as follows:

10 The body of the patient being indicated by dotted lines 14 in Figs. 2, 3, 4, the heavy fabric sheet 7 lashed between the bars 6, 6 lies flat upon the mattress and the patient 25 rests upon the sheet 7.

15 Turning the crank 11 lifts the bars 6, 6 simultaneously to the position shown in Fig. 3. The mattress is then slid out from the bedstead sidewise along the rails 4 and is 30 removed, as indicated by the dotted lines in Fig. 3.

20 A bath tub can be placed under the bedstead, as shown in Fig. 4, and the bars 6 are lowered. They slowly move toward each 25 other as they descend, the sheet descends into the bath tub, forming a trough to hold the patient securely while he is immersed in the bath. He is lifted by reverse movement of the shaft 10. The wet sheet 7 is changed, 30 while the patient is supported on it, by unfastening the lashings 7b at the foot of the bed, applying a new sheet, as shown by dotted lines in Fig. 1, and lashing it in place as fast as the successive lashings 7b of sheet 7 35 are released.

35 In this manner only a small part of the length of the patient's body is left unsupported at any one time during the changing of the sheet, and a dry sheet can be quickly substituted without disturbing the patient.

40 If it is desired to change the patient's position somewhat it can be done by slightly raising one of the bars 6, giving his body a slight tendency to roll and he can thus be turned 45 from side to side with practically no force being exerted upon him by the hands of the attendants.

45 The mattress is replaced after the tub is removed, and the patient is then lowered until he is resting upon the mattress.

50 Having thus described my invention, what I claim and desire to secure by Letters Patent is:

55 1. A bed having in combination a head-piece, a foot-piece, a mattress, mattress-supports on the head and foot-pieces respectively, a pair of arms pivotally connected to the head-piece, a second pair of arms pivoted to the foot-piece above said mattress supports, 60 bars connecting the outer ends of said arms and positioned normally at the longitudinal edges of the mattress, a flexible sheet removably secured to and adapted to be stretched in a horizontal position between said bars above 65 said mattress supports and substantially in

the plane of said pivotal connections and also adapted to be shaped hammock-wise by downward and inward movement of said arms and bars to a position below said mattress supports, and actuating means for said bars.

70 2. A bed having in combination a head-piece, a foot-piece, a mattress, mattress supports on the head and foot-pieces respectively, arms pivoted to fixed supports above said mattress supports, bars connecting the outer 75 ends of said arms and positioned normally at the longitudinal edges of the mattress, a flexible sheet removably secured to and adapted to be stretched in a horizontal position between said bars above said mattress supports and substantially in the plane of said pivotal connections and also adapted to be shaped hammock-wise by downward and inward movement of said arms and bars to a position 80 below said mattress supports, and actuating 85 means for said bars.

90 In testimony whereof, I affix my signature.
RICHARD STAUDT.
